UNITED STATES PATENT OFFICE.

TEMISTOCLE E. MELA, OF SACRAMENTO, CALIFORNIA.

MAIL-BOX.

1,062,785.

Specification of Letters Patent.

Patented May 27, 1913.

Application filed September 26, 1912. Serial No. 722,491.

To all whom it may concern:

Be it known that I, TEMISTOCLE E. MELA, residing at Sacramento, in the county of Sacramento and State of California, have 5 invented certain new and useful Improvements in Mail-Boxes, of which the following is a specification.

This invention, which in its general nature relates to improvements in letter boxes, 10 more particularly has reference to that type of mail boxes having gravity dropped doors and that automatically discharge the contents of the box through the bottom thereof and my said invention seeks to provide a 15 simple, economically made box of the general character stated, and in which is included a convenient and quickly operated means for simultaneously releasing the drop bottom of the box and the time of mail 20 collection indicator holding devices.

With other objects in view, that will hereinafter appear, my invention consists in the peculiar combination and novel arrangement of the parts hereinafter fully explained, 25 specifically pointed out in the appended claims and illustrated in the accompanying drawing, in which,

Figure 1 is a perspective view of a mail box constructed in accordance with my invention, parts of the same being in the closed or normal position. Fig. 2 is a cross sectional view of my improved mail box, the parts being adjusted for discharging the box contents into the mail bag. Fig. 3 is a perspective view, that illustrates in detail, the 30 general construction of the drop bottom lock devices and the coöperating indicator closure releasing and holding devices. Fig. 4 is a perspective view of the slidable lock 35 bolt. Fig. 5 is a perspective view of the key controlled cylinder for releasing the lock bolt and indicator cover members hereinafter referred to.

In the practical construction, the box 1 40 is preferably of square or rectangular shape and formed with an open bottom that is closed by a hinged drop door 2, the latter being so hung on the box that when opened it hangs from the rear edge of the box to 45 facilitate the ready discharge of the mail matter into the collecting sack which latter is slipped over the lower end of the box when collecting the mail, see Fig. 2.

4 designates the mail receiving inlet, located at the top of the box and provided 50 with the usual drop guard or shield 5.

6 designates a dial located below the mail inlet, for indicating the times for making the mail collections, and the same is normally closed by a glass cover 60 hinged at 60 the lower end whereby to drop by gravity when released, in the manner presently explained.

7 designates a supplemental indicator plate located below the dial 6 and closed by 65 a glass cover 70, the said space, in practice, being utilized for displaying special notices.

In my improved construction of mail box, I have provided for simultaneously dropping the hinged bottom 2 and the dial cover 70 60, so that it will be impossible for the postman to collect the mail without noticing the dial and thereby draw his attention to the resetting of the dial for the next collection, and for such purpose I employ the locking 75 devices best shown in Fig. 3. The aforesaid devices comprise a slide bolt 8 (mounted in a housing portion 80 formed on the front wall of the box 1) and which is normally forced inwardly by a coiled spring 9, that 80 takes around a stem 81 on the bolt that slides through an aperture 82 in the box front when the bolt is forced back against the tension of its pusher spring 9. Bolt 8 has a beveled edge 90 to allow for the ready snapping 85 of the door 2 to its closed position when swung up. For guiding the bolt it has lateral lugs 83 that engage grooves 84 in the housing provided therefor.

10 designates a latch hinged at 11 to the 90 inside of the front wall of the box, its free end being held from excess movement by a guard 12 on the said wall and normally swung to the upper or locking position by a 95 coiled spring 13.

14 designates a latch tongue on the dial cover 60 that projects through an aperture 65 in the mail box front, slips over, and interlocks with the latch 10, when the dial cover is swung up to its closed position.

15 designates an unlocking member horizontally disposed and rockably mounted in the bolt housing and located directly over the bolt 8, and the said member has a short lug or crank 16 for engaging a diagonally 105 disposed and downwardly curved groove 17 in the top of the bolt, the said groove and the member 16 being relatively so arranged, whereby when the member 15 is turned in one direction, see arrow X, the bolt 8 will 110 be slid back to release the drop door 2. Member 15 has a horizontal key set 17^a in

one end that alines a key hole 18 in the box front.

19 designates a key having its shank formed to pass through the key hole into the 5 key seat 17^a.

Member 15 has a crank member 20 with which joins one end of a flexible connection 21 that extends up and fastens to the free end of the latch 10.

10 By reason of the peculiar construction and the coöperative arrangement of the parts that constitute my improved letter box it is apparent that when collecting the mail all that is required of the postman is that he 15 insert the key, give the member 15 a partial turn for simultaneously releasing the door 2 to drop the mail into the sack and for pulling down the latch 10 to release the drop cover 60. The dropping of the latter and 20 the requirement that it be closed being sufficient to attract the attention of the postman to the resetting of the dial and since access cannot be had to the dial until the door or cover 60 is dropped it is apparent that 25 should the next collection be, say, 3.30 p. m., and it is desired to post a letter at 3.35 p. m. should the dial show 3.30 p. m. it is evident that the 3.30 p. m. collection has not been made.

30 What I claim is:

1. In a mail box, a locked closure member for the discharge outlet of the box, an indicator for the said box, a locked cover for the said indicator, key controlled means operable 35 from the outside of the box for simultaneously releasing the closure member for the mail outlet and the cover for the indicator, said means including a slideable spring snap bolt for engaging the closure member, a 40 latch for holding the indicator cover to its closed position, and a key engaged device that coöperates with the snap bolt and the latch and adapted to release the closure member and the latch.

45 2. In a mail box, a locked closure member for the outlet of the mail box, an indicator for the said box, a locked cover for the said indicator, means operable from the outside of the box for simultaneously releas-

ing the closure member for the mail outlet 50 and the cover for the indicator, the said means including a slideable snap bolt, a spring that normally holds the bolt to its locking position, the said bolt having a cam-way and a rocker device, said rocker device 55 being key actuated from the outside of the box and including a member for engaging the camway in the bolt whereby when the said device is rocked under key action the bolt is slid back to a releasing position and 60 against the tension of its engaging spring.

3. In a mail box, a locked closure member for the outlet of the said box, an indicator on the outside of the box, a normally locked cover for the said indicator, said cover 65 being hinged to swing down by gravity when released, means operable from the outside of the box for simultaneously releasing the closure member for the mail outlet and the cover for the indicator, said means including a slideable snap bolt, a latch for holding the indicator cover to its closed position and an actuated device that coöperates with the snap bolt and the latch and adapted under key action to release the closure member and 70 the latch.

4. In an open bottom mail box, a hinged closure member for the said bottom, a spring snap bolt for locking the closure member, an indicator on the face of the box, a gravity 80 dropped hinged cover for the said indicator, a latch device for holding said cover to its closed position, said device including a latch lever pivotally mounted on the inside of the box, the aforesaid snap bolt having a 85 diagonally disposed groove, a member rockably mounted over the bolt and having a keyway for receiving the actuating key, the said rocker member having a projection for engaging the said diagonal groove whereby 90 to shift the said snap bolt and having a crank extension and a connecting member that joins the latch with the said crank extension on the rocker member.

TEMISTOCLE E. MELA.
